DRIVE FOR TRANSIT CONCRETE MIXERS

Filed Oct. 20, 1926

2 Sheets-Sheet 2

UNITED STATES PATENT OFFICE.

CHARLES L. REYNOLDS, OF SEATTLE, WASHINGTON, ASSIGNOR TO HIMSELF AND
WILLIAM E. SMITH, OF SEATTLE, WASHINGTON.

DRIVE FOR TRANSIT CONCRETE MIXERS.

Application filed October 20, 1926. Serial No. 142,874.

My invention relates to transit concrete mixers, that is, mixers which are arranged to receive a load of aggregates, cement and water at a supply source, for the transport 5 to a job, transforming them en route, or upon arrival, into mixed concrete, ready for use.

Such mixers employ the power of the engine of the automobile truck upon which 10 they are mounted, to revolve a mixing element, as a drum or series of paddles, at will. They ordinarily have the drum or like container mounted upon a dumping frame, whereby the finished mixture may be 15 expeditiously dumped by gravity, assisted perhaps by the rotation of the mixer element, and it has been found highly desirable to rotate such a mixer element while the dumping frame upon which it is supported is 20 tilted, to completely cleanse it. Owing to the high angle to which such a container must frequently be tilted to remove the wet, clinging mixture, ordinary drive means have proven ineffective. It is my chief object, 25 therefore, to provide a drive means for such a driven mixer element, mounted upon a tiltable dumping frame, whereby it may be driven from the engine, mounted upon the chassis, at any angle to which it may be 30 tilted, and whereby it may be driven during the tilting operation, as the dumping progresses.

A further object is the provision of a 35 drive for such a mixer which is simple, which is easily controlled, and one in which provision is made for accommodating the inherent back-lash developed in the mixer drum when immediately after forward revolution is halted, it tends to rotate back- 40 wards, due to the unbalanced condition of the materials within.

A further object is the provision of drive 45 means for such a mixer permitting the application of the drive at any point in the length of the drum itself, or permitting such application at a plurality of points.

My invention comprises the novel parts 50 and the novel combinations and arrangements thereof, as shown in the accompanying drawings, described in the specification, and more particularly as defined in the claims terminating the same.

In the accompanying drawings I have 55 shown two alternative forms of my invention.

Figure 1 is a side elevation of the rear end of an automobile truck with my invention mounted thereon, the near wheel of the truck being omitted.

Figure 2 is a section substantially on line 60 2-2 of Figure 1.

Figure 3 is an axial section along the pivot axis of the dumping frame.

Figure 4 is a view similar to Figure 1, showing an alternative form of drive for 65 the mixer.

Figure 5 is a plan view substantially along the line 5-5 of Figure 4.

Figure 6 is a detail elevation along the line 6-6 of Figure 5, showing parts in the 70 positions they would assume with the mixer partly elevated.

It will be understood that the invention is chiefly concerned with the manner in which a mixer element, as for example a drum 1, 75 which is mounted upon a dumping frame 2, may be driven from a motor, of which the rear end 31 is shown, mounted upon the chassis 3 of an automobile truck, or from a shaft 30 or a power take-off, usually provided on heavy-duty trucks, the drive being through the pivot axis 20 of the dumping frame 2 upon the chassis 3 in such a manner that rotation of the mixer drum 1 may continue during dumping and at any dumping 85 angle, as well as during the time when the mixer drum sets level upon the chassis.

Different makes of trucks will necessitate 90 different power take-offs. In the particular type of truck illustrated, the transmission is enclosed within a casing 32, set amidships of the truck and connected by the shaft 30 with the motor shaft. The truck is then provided with a propeller shaft 33 connecting the transmission within the housing 32 to a 95 differential contained within the housing 34 on the rear axle of the truck. In other makes of truck the transmission housing may be continuous with the motor casing.

In the form shown the power may be 100 taken from the shaft 30 by suitable means, such as the sprocket 35 upon the shaft 30 connecting by a chain 42 with the sprocket 41 upon a shaft 4, which is journaled on the chassis 3, as illustrated at 36. Clutch elements 43 and 44 are provided, by means of which the sprocket 41 may be connected at will to rotate the shaft 4 or left loose thereon; a control lever 40 is illustrated as a conventional means of controlling the keyed-on 110

clutch element 43. By this, or any equivalent means, power is taken from the motor 31 and is delivered at the pivot 20 of the dumping frame 2.

8 The mixer element may likewise vary considerably in its characteristics. Paddles rotating in an open hopper have been proposed for such a purpose, and drums rotating in a cradle on the dumping frame, and 10 provided with mixing baffles, as indicated at 10 in Figure 2, have also been proposed. Either may be employed so far as the present invention is concerned, although only the revolving drum type has been illustrated 15 herein.

The drum is provided with two or more annular tracks 11, secured thereto, and rollers 12 mounted in stanchions 13 or like framework, support and guide the shell 20 though their engagement with the flanged tracks 11. Thus is the revolute drum 1 cradled upon the dumping frame 2. As illustrated, particularly in Figures 1 and 4, a water tank 5 is supported from the stanchions 13 and is connected by a pipe 51 to the interior of the drum, preferably through its forward end. A valve 52 controls communication between the water tank and the interior of the drum. The dumping frame 30 2 is arranged for tilting by suitable means such as the depending arm 21, to which is connected a cable 22 leading to an upright hoist (not shown). This type of construction and drive lends itself readily to an 35 underbody hoist, which may be employed if desired.

In Figures 1, 2 and 3, the drive for the drum 1 has been shown as a worm and pinion drive, the worm 6 being suitably secured to the drum 1, as by the bolts 61, and meshing with a worm pinion 60 journaled coaxially with the pivot axis 20 of the dumping frame 2. As is best shown in Figures 2 and 3, the pivot axis is illustrated as a rod 45 20 extending through the dumping frame 2 near its rear end, and being received in brackets 37 secured upon the chassis 3. Employing such a construction, the pinion 60 is formed as a part of or keyed upon a 50 sleeve 62, which sleeve, in addition to the pinion 60, has secured upon it a suitable means for taking power from the longitudinal shaft 4.

55 Perhaps the most convenient drive means are simple bevel gears, a gear 45 being shown on the shaft 4 meshing with a gear 63 keyed upon the sleeve 62. Collars 64 secured upon the pivot rod 20 take the end thrust in the sleeve 60. It will be understood, of course, that suitable anti-friction bearings may be employed at such points as they may be required, and it may be understood also that the various gears may be encased fully or partly, or run in a bath of 60 lubricant.

The drive shown in Figures 1, 2 and 3, and which has just been described, is a simple drive connection and a most direct one from the engine to the drum 1. It has the disadvantage in certain types of mixtures 70 that the drum 1 may not roll backwards, inasmuch as the worm and pinion drive is not reversible. It will be understood that the baffles 10 cause the material to ride up on one side of the drum as the drum rotates, and 75 when the rotation of the drum ceases, the tendency of this unbalanced load is to reverse the drum until the load lies substantially level.

In cases where this action of the load is a 80 serious factor, the drive shown in Figures 4, 5 and 6 may be adopted. In this form a large sprocket 7 is secured to the drum 1 at any point in its length; in fact, two or more such sprockets may be employed if it is desired to drive the drum at more than one point in its length. A smaller sprocket 70 85 is secured upon a shaft 72, journaled at 71 upon the dumping frame 2, and the shaft 72 is arranged to be rotated through the 90 pivot axis 20, as by means of bevel gears 73 and 74. In this type of drive the bevel gear 74 replaces the worm pinion 60 in the drive previously described and, as in the case of the pinion 60, the gear 74 is keyed to the 95 sleeve 62, which is driven in the manner heretofore described or in any other suitable manner.

It will be understood, of course, that a chain 75 connects the sprockets 7 and 70, and 100 this chain inherently permits some slack and may, in addition, be provided with shear pins. Further, there being no irreversible connection between the drum 1 and the clutch 43-44, any tendency for the drum to 105 rotate in a reverse direction when the clutch referred to is thrown out, will merely cause the drum to rotate backwards until the materials within have reached a level position.

It will now be clear that the drive from 110 the motor to the drum through the pivot at 20 is operable at any angle of the dumping frame 2. It operates equally well when the dumping frame lies on the chassis 3 as when it is tilted substantially perpendicular, as 115 might at times be required to dump a stiff mix such as is used for paving. It will also work while the tilting is in progress, and hence by rotating the drum during tilting, the baffles 10 will assist in breaking up the 120 mix and in cleansing the drum automatically. It will be understood, of course, that the delivery opening 15 at the end of the drum is ordinarily closed by a door 16 to prevent leakage during transit.

125 What I claim as my invention is:

1. The combination with a road vehicle having a source of power mounted thereon, a dumping frame pivoted by its rear end upon the vehicle frame, a mixer including 130

a movable mixer element supported upon said dumping frame, a rotary member coaxial with but movable independently of the pivot of said dumping frame, means operatively connecting said rotary member with the power source, and power transmission means operatively connecting said rotary member with said mixer element, and including a shaft journaled on the dumping frame.

2. The combination with a road vehicle having a source of power mounted thereon, a dumping frame pivoted upon the vehicle frame, a mixer drum revolvably cradled upon said dumping frame, a rotary member journaled coaxially with but movable independently of the pivot means of said dumping frame, and power transmission means operatively connecting said power source to the drum, to revolve the latter, through said rotary member.

3. The combination with an automobile chassis, a dumping frame pivoted thereon, a mixer drum revolvably supported upon said dumping frame, a sleeve journaled coaxially with but movable independently of the pivot of said dumping frame, means operatively connecting one end of said sleeve with the automobile engine to rotate the sleeve at will, and means associated with the opposite end of said sleeve and operatively connected to said drum to revolve the latter as the sleeve is rotated.

4. In a concrete mixer, in combination with the chassis and the engine of an automobile, a dumping frame, a transverse pivot rod connecting the rear ends of said chassis and said dumping frame, a sleeve journaled on said pivot rod, a mixer drum revolvably sup-

ported on said dumping frame, operative connection between said sleeve and said drum to revolve the latter, a longitudinal shaft journaled upon said chassis and operatively connected to said sleeve, and means operatively connecting said shaft to the engine to revolve said drum at will from the engine.

5. In a concrete mixer, in combination with the chassis and the engine of an automobile, a dumping frame pivoted thereon, a mixer drum revolvably supported upon said dumping frame, a rotary member journaled coaxially with the pivot of said dumping frame, means operatively connecting the engine with said rotary member, to rotate the latter at will, a shaft journaled upon said dumping frame and operatively connected to said rotary member, a sprocket wheel upon said shaft, a second sprocket wheel upon said drum, and a chain connecting said sprocket wheels.

6. In a concrete mixer, in combination with an automobile truck chassis and propelling mechanism, a dumping frame pivotally mounted upon the chassis, a mixer element revolvably cradled upon said dumping frame, and power transmission means including a shaft journaled upon said dumping frame, and operatively connecting the propelling mechanism on the chassis with said mixer element on the dumping frame through the pivot axis of the dumping frame, but by independently movable means.

Signed at Seattle, Washington, this 13th day of August, 1926.

CHARLES L. REYNOLDS.
